DISPLAY RACK

Newell G. Hurlbut, Joplin, Mo.

Application May 20, 1941, Serial No. 394,376

1 Claim. (Cl. 211—125)

My invention relates to display racks for flowers, the invention being designed as an improvement over the support forming the subject matter of my copending application Serial No. 320,919, filed February 26, 1940, which has terminated in U. S. Patent 2,246,441 on June 17, 1941, to which attention is invited.

The principal object of the instant invention is to provide a simply constructed rack for supporting a large number of usual floral sprays provided for funerals in fanwise arrangement at different levels from the floor and which is equipped for supporting such sprays in a wide variety of different arrangements to form different color combinations.

Another object is to provide a device of the character and for the purpose above set forth which is readily foldable into compact form for carrying or storage when not in use and which may be easily unfolded and set up when desired.

To the accomplishment of the above, and subordinate objects presently appearing, a preferred embodiment of my invention has been illustrated in the accompanying drawing, set forth in detail in the succeeding description, and defined in the claim appended hereto.

In said drawing:

Figure 1 is a view in perspective of the preferred embodiment of my invention unfolded and set up for use.

Figure 2 is a fragmentary view in perspective of one of the spray supporting rods and the fastener thereon, and

Figure 3 is a fragmentary view in elevation of another of said rods.

Reference being had to the drawing by numerals, the rack of my invention includes a stand 1 similar to the usual music rack stand and including upper, lower, and an intermediate section, 2, 3, and 4, telescopically related for relative sliding adjustment to increase or diminish the height of the stand as desired. The lower and intermediate sections 3, 4 are provided with the usual collars 5 and set screws 6, the latter for establishing the adjusted positions of the sections. The lower section 3 is adapted to be supported by the usual tripod arrangement of legs 7 having their inner ends pivoted, as at 8, to a collar 9 slidable on the section 3 so that said legs may be folded alongside said section. A set screw 10 is provided in the collar 9 for securing the latter to the section 3 in the folded or unfolded positions of said legs 7. The usual pivoted braces 11 are provided between the legs 7 and said section 3.

The upper section 2 comprises a light gauge elongated tubular rod adapted to be extended above the intermediate section 3 to form together with other rods presently described a fan-like flower supporting assembly.

Suitably secured to the upper section 2, as indicated at 12, and centered relative thereto to extend equidistantly upon opposite sides thereof is a substantially semi-circular flat metal plate 13 arranged so that when the rack is set up its curved edge will be uppermost.

A plurality of light gauge tubular rods 14 are pivoted as at 15, to the plate 13 adjacent the curved edge thereof and with the pivots 15 spaced equidistantly around said edge upon opposite sides of the section 2, the arrangement being such that the rods 14 may be unfolded fanwise in radially extending position relative to the plate 13 upon opposite sides of the section 2, or, folded 20 side by side when not in use substantially parallel with and alongside the section 2. As will be understood, the rods 14 are preferably of the same length and the section 2 above the plate 13 is the same length as the rods 14.

Pairs of links 16 connect the rods 14 and section 2 together in pairs, each pair of links being pivotally connected together at inner ends thereof at 17 and having its outer ends pivoted to the appropriate pair of rods 14 or the section 30 2 as the case may be, as represented at 18, the pivotal connections 18 being arranged at substantially the same radial distance from the plate 13 so that when the rods 14 are unfolded, said rods will be equidistantly spaced apart.

35 A U-shaped fastener link 19 is pivoted, as at 20, to the outer end of one of the outermost rods 14 for swinging over the outer ends of the remaining rods 14 when the latter are folded together to thereby hold the rods in folded position.

40 Each rod 14 is provided with a plurality of latterly extending pins 21 spaced equidistantly along the same, all of the pins 21 extending from the same side of said rods. Preferably the pins 21 have the form of tenpenny nails of suitable length extended through the rods 14 and welded thereto, the welding not being shown. Similar pins 21 are provided on section 2.

The use and operation of the invention will be readily understood. When the rack is set up and 50 unfolded, as illustrated in Figure 1, the floral sprays, not shown, are hung on the pins 21, either pinned thereon or hung loosely as desired. The fanwise arrangement of the rods 14 and the spacing of the pins 21 provide for hanging a large number of the sprays in varied arrangement to

produce different color effects as will be clear. All of the rods 14 may be used or only a selected number of intermediate rods if desired. When using the intermediate rods 14, the outermost ones may be folded separately in a manner which will be clear. When the rack is not in use, the rods 14 may be folded side by side by breaking the joints 18 of the pairs of links 16 in the usual manner and folding said rods on their pivots 15. The legs 7 and braces 11 may then be folded alongside the section 3 of the stand 1 and the sections 2 and 4 adjusted inwardly of the section 3 to collapse the stand 1 into a compact unit which, together with the folded rods 14 may be accommodated in a relatively small storage space.

The foregoing will, it is believed, suffice to impart a clear understanding of my invention without further explanation.

Manifestly the invention, as described, is susceptible of modification without departing from the inventive concept and right is herein reserved to such modifications as fall within the scope of the subjoined claim.

What I claim is:

A flower display rack comprising a foldable stand including an elongated rod section adapted to be disposed in upright position, a segmental plate fixed in said section to extend equidistantly upon opposite sides thereof intermediate the ends of the section with its arcuate edge uppermost, a plurality of rods pivoted at inner ends thereof on said plate upon opposite sides of said section with said ends spaced along said edge whereby said rods are swingable into and from outwardly diverging fanwise relation, means to limit swinging of said rods into diverging relation comprising pivoted links, pins on said rods and section for hanging floral sprays thereon, and means to lock said rods together against outward swinging comprising a loop member on one rod swingable over the outer ends of the other rods when said rods are swung from diverging relation.

NEWELL G. HURLBUT.
